UNITED STATES PATENT OFFICE.

HARRY C. FOSTER, OF CONNERSVILLE, INDIANA, ASSIGNOR, BY DIRECT AND MESNE ASSIGNMENTS, OF ONE-HALF TO INDIANA LAMP CORPORATION, OF CONNERSVILLE, INDIANA, A CORPORATION OF DELAWARE, AND ONE-HALF TO GENERAL MOTORS CORPORATION, OF DETROIT, MICHIGAN, A CORPORATION OF DELAWARE.

LAMP FOCUSING.

Application filed January 29, 1925. Serial No. 5,531.

This invention relates to lamp focusing and is herein shown as embodied in a focusing device for adjusting the lamp of an automobile headlight.

5 On automobile headlights, it is common practice to provide lamp focusing devices but these cannot be attached, as a complete assembled unit, to a lamp structure; they require the assembly of some parts from inside 10 the reflector or casing and of others from outside the reflector or casing.

One of the objects of the invention, therefore, is to provide a focusing device that can be completely assembled and then, without 15 removing any parts, attached to a casing or the like from one side thereof. Another object is to provide a focusing device which can be very quickly attached to or removed 20 from the lamp structure and this without operating any screws, bolts or other special fastenings.

To these ends and also to improve generally upon devices of the character indicated my invention consists in the various 25 matters hereinafter described and claimed.

In the drawings, Figure 1 is a side elevation, partly in vertical section, of a headlight.

Figure 2 is a rear view, broken away. 30 Figure 3 is a central vertical section.

Figure 4 is a rear view of a portion of the casing with the focusing device removed.

Referring to the drawings, the numeral 10 indicates a reflector with a sleeve 12 extending rearwardly from its middle portion and all enclosed in a lamp casing 14. The sleeve 12 slidably receives a lamp socket 16 carrying the usual lamp bulb 18. The sleeve 12 is slotted on its under side at which point 40 a right angular plate 20 is attached to the lamp socket 16. One angle of the plate is threaded to receive an adjusting screw 22 having an enlargement 24, preferably an integral collar, outside of which the screw is 45 slotted, as at 26, so it can be turned.

On a wall member 28, which might be the reflector but is preferably the rear wall of the casing 14, is an opening 30 of a size to allow the enlargement or collar 24 to pass. 50 The opening can be conveniently formed by cutting a slot in the wall and then extruding the metal in opposite directions from the

body of the wall. This forms, adjacent to the opening, two projections 32 and 34, the first affording a seat or abutment for the 55 inner side of the enlargement or collar 24 and the other covering the upper part of the collar and forming an abutment and shield for its outer side. The projections prevent axial movement of the screw 22 but 60 allow its rotation. A semicircular edge 36 on the projection 32 conforms to an unthreaded portion of the screw 22 in front of the enlargement or collar 24.

Surrounding the screw 22 is a coil spring 65 38 abutting at one end against the plate 20 and abutting at the other end against a dished washer 40. The washer 40 has its concave side facing rearwardly to fit against the front face of the extruded projection 32, 70 thus holding the screw and attached parts yielding in a substantially horizontal position and also furnishing means which would prevent undesired axial movement of the screw without using the projection 34. 75

The focusing device, comprising, for example, the screw 22, washer 40, spring 38, plate 20, and socket 16 is assembled as a unit and attached to the casing before the reflector or the lamp bulb is applied. The 80 screw 22 is tilted downwardly towards the front in order that the collar 24 may pass through the opening and engage behind the projection 32. During this operation, the washer 40 will yield against the tension of 85 spring 38 to permit the projection 32 to come between the collar and the washer. The reflector is then inserted in the casing, the sleeve 12 being slipped over the socket 16 and centering the latter. The lamp bulb is 90 then placed in the socket.

I claim:

1. In a device of the character described, in combination, a reflector, a lamp movable with respect to the reflector, a rotary lamp 95 adjusting member connected to the lamp and having an enlargement, a lamp casing, and offset projections on the casing detachably engaging axially spaced sides of said enlargement, to hold said lamp adjusting member against axial movement.

2. The combination of a lamp casing having a slot formed in a wall thereof, the material of the casing at one side of the slot

being offset from the material at the other side of the slot, and a rotatable lamp adjusting member mounted in said slot and provided with means for engaging the adjacent surfaces of the opposite edges of the slot to hold the member against axial movement.

3. In the combination as defined in claim 2, a spring pressed clamping device mounted 10 on said rotatable lamp adjusting member adapted to yieldingly engage the inner surface of the casing to hold the adjusting member in adjusted position.

4. The combination of a lamp casing, a reflector in the casing, a lamp adjustable in the reflector, adjusting means for the lamp comprising an adjusting screw, a projection

extending from a wall of said casing and forming therewith a socket accessible from the interior of the casing for receiving the head of said screw to hold it in position, said screw being normally engaged with said projection from the front of the casing, and said casing being provided with an aperture aligned with said screw to permit access 25 to the head thereof for manipulation.

5. The combination as defined in claim 4, and yieldable means mounted on said adjusting screw for engaging the inner wall of the lamp casing to prevent outward axial 30 movement of said screw.

In testimony whereof I affix my signature.

HARRY C. FOSTER.
